UNITED STATES PATENT OFFICE.

HENRIETTA J. LYON, OF NEWARK, NEW JERSEY.

ATTACHMENT FOR PANTS.

SPECIFICATION forming part of Letters Patent No. 349,657, dated September 21, 1886.

Application filed March 6, 1886. Serial No. 194,265. (No model.)

To all whom it may concern:

Be it known that I, HENRIETTA J. LYON, of Newark, in the county of Essex and State of New Jersey, have invented certain new and 5 useful Improvements in Attachments for Pants, of which the following is a specification.

This invention relates to an improved attachment for pants of that class which are worn by children, so that the strain on the 10 shirt or waist when sitting or stooping is reduced; and the invention consists of the combination, with a pair of pants, of a transverse lower strip attached to said pants, a transverse upper strip, and elastic bands connecting said 15 strips, said elastic bands being arranged in pairs, with an opening or button hole formed between each pair of bands.

The invention consists, further, of certain details of construction and combination of parts, 20 which will be described hereinafter, and finally pointed out in the claims.

In the accompanying drawings, Figure 1 represents a perspective view of a pair of pants with my improved attachment. Figs. 2 and 3 25 are side views of the attachment, drawn on a larger scale; and Fig. 4 is a vertical transverse section on line $x-x$, Fig. 2.

Similar letters of reference indicate corresponding parts.

Referring to the drawings, A represents a 30 pair of pants with my improved attachment, which consists of two transverse strips, B and C, and elastic bands D D, which connect said strips. The lower strip, B, is attached to the 35 pants, while the upper strip, C, connects the upper ends of the bands D D. The bands D D are arranged in pairs, the bands of each pair being located close to each other, so as to form an opening or button-hole between each pair 40 of bands D. The central pair of elastic bands D may be made longer than the remaining bands, and extended below the lower strip, B, and attached at the lower end to the body of the pants, so as to be capable of greater extension 45 at that point, which is the point of greatest strain, as shown in Fig. 2. At each end of the attachment non-elastic connecting-bands

D' may be arranged, said non-elastic bands being used at those points where it is not required that the attachment should "give" in 50 the same manner as at points at which the rear part of the pants on which the greatest strain is exerted.

My improved attachment has the advantage that it can be quickly and easily buttoned to 55 the shirt or waist or unbuttoned therefrom. It can be manufactured at comparatively small expense, as no stitched button-holes are required, which render these attachments expensive. The attachment forms a kind of 60 skeleton band, which is especially adapted for use with cheaper goods, to which it imparts all the advantages connected with the more expensive waistband attachment.

Having thus described my invention, I claim 65 as new and desire to secure by Letters Patent—

1. The combination, with a pair of pants, of an attachment consisting of a transverse lower strip attached to said pants, a transverse top strip parallel to the lower strip, and elastic 70 bands connecting said strips, said bands being arranged in pairs closely to each other and having an opening forming a button-hole between each pair of bands intermediately between the strips, substantially as set forth. 75

2. The combination, with a pair of pants, of an attachment consisting of a transverse lower strip attached to said pants, a transverse top strip parallel to the lower strip, and elastic bands connecting said strips, said bands being 80 arranged in pairs and having an opening or button hole formed between each pair of bands and intermediately between said strips, the central pair being of greater length than the remaining pairs and attached at the lower end 85 to the body of the pants, substantially as set forth.

In testimony that I claim the foregoing as my invention I have signed my name in presence of two subscribing witnesses.

HENRIETTA J. LYON.
